(57) **CLAIM**

The ornamental design for a connection box for a control unit, as shown and described.

DESCRIPTION

FIG. 1 shows a front elevational view of an embodiment showing a connection box for a control unit.

FIG. 2 shows a perspective front view of an embodiment of the connection box for a control unit.

FIG. 3 shows a perspective rear view of an embodiment of the connection box for a control unit.

FIG. 4 shows a perspective left rear side view of an embodiment of the connection box for a control unit.

FIG. 5 shows a perspective right rear side view of an embodiment of the connection box for a control unit.

FIG. 6 shows a perspective left side view of an embodiment of the connection box for a control unit.

FIG. 7 shows a perspective right side view of an embodiment of the connection box for a control unit.

FIG. 8 shows a perspective top side view of an embodiment of the connection box for a control unit; and,

FIG. 9 shows a perspective bottom side view of an embodiment of the connection box for a control unit.

1 Claim, 9 Drawing Sheets
